REMOTE-CONTROL DEVICE

Charles V. Koons, Philadelphia, Pa., assignor, by
mesne assignments, to American Engineering
Company, Philadelphia, Pa., a corporation of
Pennsylvania

Application December 26, 1941, Serial No. 424,552

4 Claims. (Cl. 60—54.6)

This invention relates to remote control devices adapted for use on ships to control the operation of the steering or other mechanisms thereof and when so used are generally known as telemotors.

One object of the present invention is to provide a simplified and generally improved remote control device or telemotor of the hydraulic type.

Another object is to provide a compact and unitary control device wherein the parts of the forward end thereof are enclosed by a common casing and to provide within said casing a reservoir for the fluid utilized in the system.

Another object is to provide in a device of the stated character novel and simplified valve constructions.

Other and further objects will become apparent as the description of the invention progresses.

Of the drawings:

Fig. 1 is an assembly view partly in section of the remote control device or telemotor comprising the present invention.

Fig. 2 is a sectional elevational view taken through the forward or control end of the remote control device, showing the arrangement of the various elements thereof.

Fig. 3 is a view partly in section taken substantially along line 3—3 of Fig. 2.

Fig. 4 is a sectional view of the shuttle valve taken substantially along line 4—4 of Fig. 5.

Fig. 5 is a sectional view taken substantially along line 5—5 of Fig. 4.

Fig. 6 is a sectional view of the by-pass valve provided at the control end of the remote control device.

Referring to the drawings, the numeral 1 indicates the entire remote control device or telemotor which consists of a forward unit 2 and an after unit 3. The forward unit 2 is usually located in the pilot house of the ship while the after unit is located adjacent the steering mechanism near the stern of the ship. As shown in Figs. 1 and 2, the forward unit 2 comprises a casing 4 having a pumping unit 5 mounted therein. Casing 4 is provided with a circular flange 6 at the lower end thereof, which seats upon a bottom plate 7. Bolts 8 extending through flange 6 and bottom plate 7 rigidly secure the unit to the deck 9 of the bridge.

Casing 4 comprises a lower, substantially cylindrical portion 10, an intermediate frusto-conical portion 11, and an upper, substantially cylindrical portion 12. As shown more particularly in Figs. 2 and 3, the pumping unit 5 and other hydraulic elements hereinafter described are

mounted in the lower portion 10 of casing 4, the pumping unit being bolted or otherwise secured to a bracket 5a integral with casing 4. The intermediate portion 11 is provided with top and bottom walls 13 and 14 respectively, and an interior cylindrical wall 15 disposed toward the right (Fig. 2) and connected to the said top and bottom walls. The cylindrical wall 15 provides a vertically disposed cylindrical chamber 16 through which the drive shaft 17 of pumping unit 5 extends. The top and bottom walls 13 and 14, interior cylindrical wall 15, and the outer frusto-conical wall 18 form a closed chamber 19, which constitutes a reservoir for the fluid utilized in the system.

The outer wall 18 of intermediate portion 11 is provided with a projecting portion 20 to which is attached a gauge 21 which registers the depth of the fluid in the reservoir 19. Gauge 21 comprises a supporting bracket 22 which extends into the interior of chamber 19 and in which a shaft 23, operatively connected to the pointer 24 of said gauge, is rotatably mounted. Shaft 23 has secured thereto one end of an arm 25 to the other end of which is secured a float 26.

Fluid is supplied to reservoir 19 through a tube 27 which extends through openings provided in the top walls 28 and 13 of top and intermediate portions 12 and 11, respectively, of casing 4. A removable plug 29 seals the upper end of tube 27 and prevents foreign matter from entering reservoir 19.

As shown in Fig. 2, the right hand side of the upper portion 12 of casing 4 is provided with a relatively large opening 30 and has secured thereto in any suitable manner, such as by bolts 31, a bearing bracket 32. Mounted in bearings 33 and 34 in bracket 32, and extending through opening 30, is a shaft 35 to one end of which is secured a steering wheel 36. The other end of shaft 35 has secured thereto a bevel gear 37 which meshes with a bevel gear 38 secured to shaft 17. Shaft 17 is mounted in any suitable bearings 39 and 40 disposed at the upper ends of chamber 16 and the upper cylindrical portion 12 of casing 4, respectively, and is operatively connected at its lower end to the gear 41 of pumping unit 5. Gear 41 and its companion gear 42 are rotatably mounted in the casing 43 of pump 5. It therefore is seen that any movement imparted to wheel 36 is imparted to the gears 41 and 42 of pump 5, causing the latter to deliver fluid to the after unit 3, as will presently be described.

Referring to Figs. 2 and 3, it will be observed that one side of casing 43 has extending there-

from a flanged fitting 45 to which is secured by bolts 46 a second fitting 47. Fitting 47 is connected to one end of a 4-way pipe fitting 49 by piping 48. The other side of fitting 49 is connected to one end of the casing 50 of a normally closed by-pass valve 51, by piping 52. The other side of the casing 43 of pump 5 has also extending laterally therefrom a flanged fitting 53 to which is secured by bolts 54 a second fitting 55. Fitting 55 is connected to one side of a second 4-way pipe fitting 56 by piping 57. The other side of fitting 55 is connected to the opposite side of the casing 50 of bypass valve 51 by piping 58.

By-pass valve 51 comprises a frustro-conical valve member 59 rotatably mounted within the casing 50 thereof, and having an opening 60 extending therethrough. When valve member 59 is in the position shown in Fig. 6, no fluid may pass therethrough. However, when the valve member is moved through an angle of ninety degrees fluid is free to pass through the opening 60 thereof. A handle 61 secured to the upper end of valve member 59 is provided for operating the latter to open or closed position.

The bottom wall 14 of reservoir 19 has provided therein a pair of threaded openings 63 and 64, the former of which is used as a drain and is normally sealed by a plug 65. Opening 64 receives a threaded pipe 66 extending upwardly from a check valve 67 which in turn is connected to the central port 68 of a shuttle valve 69. Shuttle valve 69 comprises a cylindrical body portion 70 having an enlarged opening 71 provided therein which communicates with port 68 and openings 72 and 73 extending therefrom to the outer sides 74 and 75 of said body portion, and through which extends a slidably valve member 76.

Valve member 76 consists of a pair of spaced valve elements 77 and 78 which are connected by a guiding and supporting member 79. A bolt extending through openings provided centrally of valve elements 77 and 78 and member 79 retain the parts in the position shown in Fig. 4. The sides of body portion 70 are provided with seats 81 and 82 for valve elements 77 and 78, respectively. Valve 69 also consists of a pair of end members 85 and 86 having threaded ports 87 and 88, respectively, provided centrally thereof. End members 85 and 86 are provided with dished out portions 89 and 90, respectively, to accommodate valve elements 77 and 78 and bolt 80, as shown in Fig. 4. Annular grooves 91 and 92 are respectively provided in end members 85 and 86 which receive the sides 74 and 75, respectively, of member 70 near the outer periphery thereof to effect a seal. Aligned apertures 93 are provided at the corners of each end member for receiving bolts 94 which, when tightened, draw the parts into the position shown in Fig. 4. Port 87 of end member 85 is connected to the upper end of 4-way fitting 49 by piping 95, while port 88 of end member 86 is connected to the upper end of 4-way fitting 56 by piping 96. The lower end of fitting 49 is connected to the left hand end of the cylinder 97 of motor 98 of after unit 3 by a pipe 99, while the right hand end of the cylinder 100 of motor 98 is connected to the lower end of the fitting 56 by a pipe 101.

Motor 98 is secured to a bracket 102, which, in turn may be secured to the deck of the steering compartment. Cylinders 97 and 100 are in axial alignment and have operating therein a piston 103. Secured to piston 103 intermediate the ends thereof is a crosshead 104 to which is pivotally

connected at 105 one end of link 106, the other end of which being pivotally connected to the arm 107 of a bellcrank lever 108. The other arm 109 of bellcrank lever 108 may be connected to the control mechanism for the steering or other mechanism (not shown). Crosshead 104 has secured thereto in any suitable manner a pair of threaded bolts 110 and 111. The left hand ends of bolts 110 and 111 are respectively secured to the right hand ends of a pair of rods 112 and 113, which extend through apertures provided in a pair of spaced cross members 114 and 115. Cross member 114 in the present instance is integral with bracket 102, while cross member 115 is secured to bracket 102 by a pair of rods 116. Rods 116 are provided with screw threads at the ends thereof and extend through apertures provided in cross member 115 and a vertically extending supporting member 117 of bracket 102. Nuts 118 and 119 provided at the left and right hand ends, respectively, of rods 116 secure the parts in position and permit the distance between cross-members 114 and 115 to be varied. Rods 112 and 113 are provided with threaded portions 120, 121 at the right hand ends thereof, and have provided thereon nuts 122 and 123, respectively. Also mounted on rods 112 and 113 near the right hand end thereof, and extending through apertures provided in cross member 114, 30 are sleeves 124 and 125, respectively, the right hand ends of which being in engagement with nuts 122 and 123. Secured to sleeves 124 and 125, and disposed at the left side (Fig. 1) of cross member 114, are a pair of spring seats 126, 127, 35 respectively, which receive the right hand ends of coil springs 128 and 129. The other ends of springs 128 and 129 engage spring seats 130 and 131 respectively, secured to sleeves 132 and 133 provided near the left hand ends of rods 112 and 113. The left hand ends of rods 112 and 113 are threaded, as shown at 134 and 135, and have nuts 136 and 137 respectively, provided thereon, and which engage the left hand ends of sleeves 132 and 133, respectively. Sleeves 124, 132, and 125, 133, are loosely mounted on rods 112 and 113, and consequently the said rods are free to move relative thereto.

From the foregoing description it is seen that upon movement of piston 103 to the left, crosshead 104 will cause bellcrank lever 108 to move in a clockwise direction. At the same time, nuts 122 and 123 will engage sleeves 124 and 125, causing them, as well as the spring seats 126 and 127, respectively, secured thereto, to move to the left, thereby compressing springs 128 and 129. On the other hand, when piston 103 is moved in the opposite direction crosshead 104 will cause bellcrank 108 to move in a counter-clockwise direction. At the same time, the nuts 136 and 137 provided at the left hand ends of rods 112 and 113, respectively, will engage their sleeves 132 and 133, causing said sleeves, as well as the spring seats 130 and 131 secured thereto, to move to the left, to compress springs 128 and 129. It therefore is seen that the springs 128 and 129 operate to return the parts to normal position after operation thereof. The rods 110, 112 and 111, 113 may be properly positioned with respect to crosshead 104 by adjustment of nuts 140 and 141, respectively.

From the foregoing description the operation of my improved device is thought to be apparent. However, in order to correlate the various elements thereof a brief description of the operation of the device as a whole will now be given.

To begin the operation of the device, the operator makes certain that bypass valve 51 is closed, and that the proper amount of fluid is in the system. Upon operation of steering wheel in such a direction as to cause gear 41 of pumping unit 5 to move in the clockwise direction (Fig. 3) fluid under pressure will enter fitting 45 and flow to the left hand end of cylinder 97 to motor 98 through fitting 46, piping 48, fitting 49 and pipe 99. Fluid at the right hand end of cylinder 100 will be returned to pumping unit 5 through pipe 101, fitting 56, pipe 57, and fittings 55 and 53. By this action piston 103 is caused to move to the right, which through crosshead 104 imparts a movement to bellcrank lever 108 in a clockwise direction. At the same time nuts 136 and 137 engaging the outer ends of sleeves 132 and 133, respectively, will cause a movement thereof and of the spring seats 130 and 131 secured thereto to the right, thereby compressing springs 128 and 129. In the event that the wheel 36 should now be turned in the opposite direction, causing gear 41 of pumping unit 5 to move in a counterclockwise direction (Fig. 3), fluid will now enter the right hand end of cylinder 100 of motor 98 through fittings 53, 55, pipe 57, fitting 56 and pipe 101. Fluid at the left hand end of cylinder 97 will be returned to pump 5 through pipe 99, fitting 49, piping 48 and fittings 47 and 45. By this action piston 103, together with crosshead 102, will be moved to the left, thereby effecting a movement of bellcrank lever 108 in a clockwise direction. By this action the compression previously placed on springs 128 and 129 will be relieved until the central position has been reached. Continued movement of piston 103 to the left will cause compression of springs 128, 129 through the action thereon of spring seats 126, 127, as previously described. When the wheel 136 has been restored to its neutral position, springs 128 and 129 will assure proper positioning of piston 123, and consequently of crosshead 102 and bellcrank lever 108, thereby bringing the controls of the steering or other mechanism operated thereby to neutral position.

During operation of the device it is seen that fluid from reservoir 19 may enter the system through piping 66, check valve 67, and shuttle valve 69. The check valve 67 prevents fluid in the system from backing up into reservoir 19. Valve 67 therefore constitutes an additional precaution to prevent fluid in the system from flowing into the reservoir upon a pressure rise in the system.

As shown in Figs. 2, 3 and 6, when steering wheel 36 has been so operated as to discharge fluid through fitting 45, pressure will be imposed against valve element 71, thereby causing valve member 76 to move to the right to prevent the passage of fluid therethrough. It is seen, however, that makeup fluid may enter the system through port 68, opening 73, port 88, piping 96, and fitting 56. On the other hand, when steering wheel 36 has been so operated as to cause pump 5 to deliver fluid to fitting 53, the pressure created thereby will operate against valve element 78, causing valve member 76 to move to the left, thereby preventing passage of fluid through opening 73. Under these conditions makeup fluid from reservoir 19 may enter the system through port 68, opening 72, port 87, piping 95, and fitting 49.

The bypass valve 51 is provided to disable operation of the device whenever it is desired to do so. As shown in Figs. 1 and 2, a removable

plate 150 normally closes an access opening provided at one side of the lower portion 10 of casing 4. Plate 150 is held in position by bolts 151 and has a transverse slot 152 provided therein through which the handle 61 for operating valve 51 extends.

From the foregoing description it is seen that my improved remote control device may be used not only on board ship, but also to control the operation of devices located elsewhere, when remote control thereof is desired.

While the embodiment herein shown and described is admirably adapted to fulfill the objects primarily stated, it is to be understood that the invention is not to be limited thereto, since it may be embodied in other forms, all coming within the scope of the claims which follow.

What is claimed is:

1. A remote control device comprising a fluid system, a casing, said casing comprising an upper portion, an intermediate portion and a lower portion, a wall provided centrally of said intermediate portion defining a passageway extending through said intermediate portion and communicating with said upper and lower portions, a shaft extending through said passageway and into said upper and lower portions, gearing provided in said upper portion for actuating said shaft, a pump provided in said lower portion, means operatively connecting said pump to the lower end of said shaft, and means for actuating said gearing.

2. A remote control device comprising a fluid system, a casing, said casing comprising an upper portion, an intermediate portion and a lower portion, a wall provided centrally of said intermediate portion defining a passageway extending through said intermediate portion and communicating with said upper and lower portions, a shaft extending through said passageway and into said upper and lower portions, gearing provided in said upper portion for actuating said shaft, a pump provided in said lower portion, means operatively connecting said pump to the lower end of said shaft, means for actuating said gearing, the said intermediate portion of said casing forming a reservoir for said system and means operatively connecting said reservoir to said pump.

3. A remote control device comprising a fluid system, a casing, said casing comprising an upper portion, an intermediate portion and a lower portion, a wall provided centrally of said intermediate portion defining a passageway extending through said intermediate portion and communicating with said upper and lower portions, a shaft extending through said passageway and into said upper and lower portions, gearing provided in said upper portion for actuating said shaft, a pump provided in said lower portion, means operatively connecting said pump to the lower end of said shaft, means for actuating said gearing, the said intermediate portion of said casing forming a reservoir for said system, means operatively connecting said reservoir to said pump, a shuttle valve, piping connecting one side of said shuttle valve to one side of said pump and piping connecting the other side of said valve to the other side of said pump, and means connecting said shuttle valve to said reservoir.

4. A remote control device comprising a fluid system, a casing, said casing comprising an upper portion, an intermediate portion and a lower portion, a wall provided centrally of said intermediate portion defining a passageway extending

through said intermediate portion and communicating with said upper and lower portions, a shaft extending through said passageway and into said upper and lower portions, gearing provided in said upper portion for actuating said shaft, a reversible discharge pump provided in said lower portion, means operatively connecting said pump to the lower end of said shaft, means for actuating said gearing, the said intermediate portion of said casing forming a reservoir for 10

said system, means operatively connecting said reservoir to said pump, a shuttle valve, piping connecting one side of said shuttle valve to one side of said pump and piping connecting the other side of said valve to the other side of said pump, means connecting said shuttle valve to said reservoir, a bypass valve connected to the opposite sides of said pump, and operating means for said bypass valve.

CHARLES V. KOONS.
